ADAPTER SOCKET FOR MULTILIGHT
INCANDESCENT ELECTRIC LAMPS

Gustav Herzberg, Maplewood, and Alfred F. Bahlke, Scotch Plains, N. J., assignors to Utility Electric Corporation, Newark, N. J., a corporation of New Jersey

Application May 9, 1938, Serial No. 206,758

6 Claims. (Cl. 173—347)

Many incandescent electric lamps today are manufactured with a plurality of filaments of different wattages related and combined with each other so that they may be placed in the electric circuit either separately or all together so as to secure at will illumination of varying degrees of intensity. The invention relates particularly to "multi-light" lamps wherein each filament has the same characteristics as that of 5 an ordinary one filament lamp of the same wattage, as distinguished from the old so-called "turn-down" lamps having two filaments so related that when they are connected in series one will glow while when one is short-circuited the other will 10 glow.

These "multi-light" lamps require special lamp sockets having special switches for controlling the filaments because the ordinary switch socket is adapted for use with only the more common electric lamp having one filament. Therefore, it is 15 not possible to utilize a multi-light lamp with the usual switch socket adapted for "one-light" or single filament lamps. Accordingly, in order to obtain the advantages of a "multi-light" lamp, 20 the owner of a standard or portable or other fixture having a "one-light" switch socket, generally must buy a new standard, portable or fixture equipped with a multi-light socket. This usually entails unnecessary expense in the purchase price of the new device and discarding of 25 the old one.

One object of the present invention is to provide an adapter to be inserted into an ordinary socket for one-light or single filament lamps and 30 embodying novel and improved means for mounting a "multi-light" lamp bulb, whereby to permit the multi-light bulb to be used in conjunction with said ordinary socket.

Another object is to provide an adapter of the 35 character described which shall embody a novel and improved switch for controlling the circuits through the several filaments of a multi-light lamp bulb separately or together at will.

A further object is to provide such an adapter 40 wherein the switch shall include an operating disk concentric with the adapter and having its periphery projecting beyond the outer surface of the adapter to be grasped by the fingers of an operator for operating the switch, whereby the 45 adapter shall be small and compact and the switch actuating disk shall be easily accessible and simple to operate.

Other objects are to provide a switch including 50 a novel and improved construction, combination 55 and arrangement of terminals and contact mem-

bers for controlling a plurality of circuits and which shall be simple and inexpensive; and to obtain other advantages and results as will be brought out by the following description in conjunction with the accompanying drawing. 5

Referring to said drawings,

Figure 1 is a vertical longitudinal sectional view through an adapter constructed in accordance with the invention.

Figure 2 is a horizontal sectional view on the 10 line 2—2 of Figure 1 with portions broken away for clearness in illustration.

Figure 3 is a horizontal sectional view on the line 3—3 of Figure 1.

Figure 4 is a vertical longitudinal sectional view 15 taken on a plane perpendicular to that of Figure 1.

Figure 5 is a horizontal sectional view on the line 5—5 of Figure 1.

Figure 6 is a horizontal sectional view on the 20 line 6—6 of Figure 4, and

Figures 7, 8, 9 and 10 are wiring diagrams showing the operations of the switch for controlling the filaments through a multi-light lamp. 25

Specifically describing the invention, the adapter includes a plug A to be inserted into the socket for an ordinary single filament lamp, and a socket B to receive the base of a known type of multi-light or multiple filament electric incandescent lamp C. 30

As shown, the plug A includes a hollow block 1 of electrical insulating material on the exterior of which is a screw threaded metallic shell 2 to screw into an ordinary lamp socket. The top of the plug comprises a disc 8 of insulating material set within the shell 2 on the top of the hollow block 1 and having a lug 9 projecting laterally for a purpose to be hereinafter described. The socket B includes an interiorly screw threaded metallic shell 3 into which is screwed the base of the lamp C, said shell being encased in a sleeve of electrical insulating material 4. The bottom of the socket is shown as comprising a disc of insulating material 10 that is inserted within the end of the shell 3 so that the edges of the shell 35 project beyond the disc as indicated at 11, the disc being secured in position in any suitable manner as by screws 12. 40

Between the plug A and the socket B is a switch 45 mechanism D for controlling the circuits through the filaments of the lamp C. The lamp filaments are schematically illustrated in Figures 7, 8 and 9, there being two filaments E and F having a common terminal 5 and individual terminals 6 and 7 55

respectively connected to the switch contacts in a manner to be hereinafter described.

The socket B is mounted on the plug A coaxially therewith. As shown, a disc 13 of metal abuts the outer end of the plug 1 of insulating material and is secured by a screw 130 to a rod 14 that extends coaxially through the plug and through an opening 15 in the bottom 10 of the socket. The upper end of the rod carries a nut 16 between which and the bottom 10 of the socket is interposed a compression spring 17. With this construction the socket is normally influenced toward the plug and the two elements are held together. To prevent relative rotation of the socket 15 and plug 1 may attach a link 18 to the lug 9 of the disc 8 of the plug and provide a pin and slot connection 19 between said link and the socket.

The switch mechanism D controls the circuit from the terminals of the ordinary lamp socket 20 in which the plug A is fitted, through the two filaments of the lamp C so that said filaments may be placed in circuit separately or together, or thrown out of the circuit, at will. As shown, the lamp has a common terminal for the filaments 25 E and F, this terminal being connected to the shell 20 of the lamp base. The other terminal of one of the filaments is connected to the central terminal 21 of the lamp base, while the other terminal of the other filament is connected to an intermediate terminal ring 22 on the lamp base, the three terminals 20, 21 and 22 being insulated from each other by the insulation in the base of the lamp as is known in the art.

The central terminal 21 of the lamp base separately cooperates with a central spring contact element 23 at the base of the socket B. As shown, this contact element is a U-shaped spring having one end secured on the rod 14 beneath the nut 16 and its other end overlying the end of the rod.

The intermediate terminal 22 of the lamp cooperates with a contact element 24 which comprises a conducting pin secured in and projecting upwardly from the bottom 10 of the socket and also exposed on the opposite side of said bottom 10.

The shell 20 of the lamp base cooperates with the shell 3 of the socket in the usual manner.

The outer or shell terminal 2 of the plug A is permanently electrically connected to the shell 3 of the socket B. As shown, this is effected by concentric contact rings 25 and 26 disposed at opposite sides of a switch operating disc 27 and electrically connected by rivets 28, one of the rings bearing against the edge 11 of the socket shell 3 and the other ring bearing against the edge of the plug shell 2 as indicated at 29. This contact between the parts is maintained by the spring 17.

The operating disc 27 is formed of insulating material and rotatably mounted coaxially with the plug and socket upon the rod 14. This rod is formed of two pieces 140 and 141 rigidly connected together by a dowel pin 30 of insulating material which is secured in sockets in the juxtaposed ends of the sections 140 and 141 whereby said two sections are electrically insulated from each other. The section 140 forms the central terminal for the plug A and the upper section 141 through which the central contact element 23 of the socket B is connected, may be electrically connected to the section 140 selectively by a spring finger 31 mounted on a collar 32 that is fixedly secured in a hub or boss 270 on the operating disc 27 and electrically contacting with the section 141. The spring finger selectively cooperates with contact points 33 diametrically oppositely dis-

posed on the section 140. In this way, the central contact element 23 of the socket may be selectively electrically connected to the central terminal of the plug A.

The intermediate contact element 24 of the socket may also selectively be connected with the central terminal of the plug. As shown, the conducting link 34 has one end clamped between the rod 14 and the disc 13 and its other end projecting through the disc of insulation 8 at the top of the plug. The switch operating disc 27 has a segmental contact piece 35 to electrically contact selectively with the end of the link 34. The segment 35 is connected electrically by rivets 36 to a contact ring 37 at the opposite side of the operating disc 27, and this contact ring 37 constantly electrically contacts with the intermediate contact 24 of the socket.

In operation of the adapter, it will be observed that with the plug A screwed into an ordinary lamp socket and the lamp C screwed into the socket B, the common terminal of the filaments of the lamp C will be connected continuously electrically to the shell terminal of the plug A. The contact finger 31, contact points 33, and the link 34 and the conducting segment 35 are so relatively arranged that upon rotation of the operating disc 27, the filaments E and F will be connected in circuit separately or together or both of the filaments will be thrown out of circuit.

Referring to Figure 7 it will be seen that both filaments are connected in circuit, the contact finger 31 contacting with one of the contact points 33 and the link 34 contacting the contact segment 35 and ring 31, whereby both the separate terminals 6 and 7 of the filaments E and F are connected electrically to the central terminal of the plug A. In Figure 8 only the filament E is in circuit, the contact finger 31 having been rotated out of engagement with the contact points 33, while in Figure 9 only the filament F is in circuit, the contact finger 31 having been brought into contact with the other contact point 33 and the contact segment 35 having been moved out of contact with the link 34. In Figure 10 both of the filaments are out of circuit, the contact finger 31 being out of contact with both of the contacts 33, and the contact segment 35 having been moved out of contact with the link 34.

It will be observed that the periphery of the switch operating disc 27 projects concentrically beyond the outer surfaces of the plug and socket A and B so as to be conveniently accessible for operation, and the construction, combination and arrangement of the parts provides a small, compact and relatively inexpensive device.

While we have shown and described the invention as embodied in certain details of structure, it should be understood that the structural features of the adapter may be widely modified or changed without departing from the spirit or scope of the invention.

Having thus described our invention, what we claim is:

1. An adapter of the character described comprising a plug to fit into an ordinary lamp socket and having two terminals one of which is an outer shell concentric with the plug, an electric lamp socket mounted on said plug coaxially therewith to receive the base of a lamp which has a plurality of base terminals with one end of each of a plurality of filaments connected separately to certain of said base terminals and together to another of said base terminals, the second-mentioned socket having a plurality of 75

contact elements to be engaged by said base terminals one of which is an inner shell concentric with said socket, and a switch comprising a disc of insulating material mounted to rotate coaxially between said plug and said socket and carrying contact pieces arranged to connect selected contact elements in circuit with the other plug terminal, said disc also having concentric rings to constantly electrically contact with and connect said shells, whereby the filaments may be energized separately or together.

2. An adapter of the character described comprising a plug to fit into an ordinary lamp socket and having an outer shell terminal and a central terminal, an electric lamp socket coaxially mounted on said plug to receive the base of a lamp which has a plurality of base terminals with one end of each of a plurality of filaments separately connected to certain of said base terminals and together to another of said base terminals, the second-mentioned socket also having a bottom, a central contact element, an intermediate contact element and a shell contact element to separably engage the respective base terminals of said lamp, and a switch including a disc of insulating material rotatably mounted coaxially between said socket and said plug, concentric contact rings on said disc to constantly electrically connect said shells of the plug and socket, and other contact pieces on said disc each selectively to electrically connect one or the other of said contact elements with said central terminal of the plug.

3. An adapter of the character described comprising a plug to fit into an ordinary lamp socket and having an outer shell terminal and a central terminal, an electric lamp socket coaxially mounted in said plug to receive the base of a lamp which has a plurality of base terminals with one end of each of a plurality of filaments separately connected to certain of said base terminals and together to another of said base terminals, the second-mentioned socket also having a bottom, a central contact element, an intermediate contact element and a shell contact element to separably engage the respective base terminals of said lamp, and a switch including a disc of insulating material rotatably mounted coaxially between said socket and said plug, a coaxial rod passing through said disc and connecting said plug and socket and formed of two coaxial electrically insulated sections one of which is electrically connected to each of said central terminals of the plug and said central contact element of the socket, a contact finger carried by said disc to selectively electrically connect said sections together, and other contact pieces on said disc to constantly electrically connect said shell terminals and to selectively electrically connect said intermediate contact element of the socket to said central terminal of the plug.

4. An adapter of the character described comprising a plug to fit into an ordinary lamp socket and having an outer shell terminal and a central terminal, an electric lamp socket coaxially

mounted in said plug to receive the base of a lamp which has a plurality of base terminals with one end of each of a plurality of filaments separately connected to certain of said base terminals and together to another of said base terminals, the second-mentioned socket also having a bottom, a central contact element, an intermediate contact element and a shell contact element to separably engage the respective base terminals of said lamp, said intermediate contact element of said socket extending through the bottom thereof, a conducting member electrically connected to said central terminal of the plug, a switch including a disc of insulating material coaxially mounted between said socket and said plug, means including a contact piece on said disc selectively to electrically connect said central terminal of the plug and said central contact element of the socket, a contact segment concentrically mounted on said disc selectively to electrically connect said contact member with said intermediate contact element of the socket independently of or simultaneously with connection of said central terminal of the plug with said central contact element of the socket, and a contact piece on said disc for constantly electrically connecting said shells of the plug and socket, whereby the filaments of said lamp may be energized separately or together.

5. An adapter of the character described comprising a plug to fit into an ordinary lamp socket and having an outer shell terminal and a central terminal, an electric lamp socket coaxially mounted on said plug to receive the base of a lamp which has a plurality of base terminals with one end of each of a plurality of filaments separately connected to certain of said base terminals and together to another of said base terminals, the second-mentioned socket also having a bottom, a central contact element, an intermediate contact element and a shell contact element to separably engage the respective base terminals of said lamp, and a switch including a disc of insulating material rotatably mounted coaxially between said socket and said plug, a coaxial rod passing through said disc with one end passing slidably through said bottom of the socket and the other end fixedly connected to said plug a head at one end of the rod in spaced relation to said bottom of the socket, a compression spring interposed between said head and the base of said socket, whereby said socket and plug are connected together and are yieldingly pressed against opposite sides of said switch disc, and contact pieces on said disc arranged to connect selected contact elements in circuit with said plug terminals so that said filaments can be energized separately or together.

6. The adapter set forth in claim 2 with the addition of means for yieldingly influencing said plug and socket toward opposite sides of said switch disc to maintain contact between said contact rings, said contact pieces and the corresponding contact elements.

GUSTAV HERZBERG.
